(57) **CLAIM**

The ornamental design for an orthodontic teat for feeding bottles as shown and described.

DESCRIPTION

1. Orthodontic teat for feeding bottles

1.1 : Perspective

1.2 : Right

1.3 : Back

1.4 : Left

1.5 : Front

1.6 : Top

1.7 : Bottom

The design relates to the outer appearance of an orthodontic teat for feeding bottles, wherein it has a head portion with an orthodontic shape, a body portion with outwardly projecting spaced-apart horizontal ribs, and a flanged base. In the drawings, the equal-length broken lines depict portions of the orthodontic teat for feeding bottles that form no part of the claimed design.
